SEPARATING PROCESS AND APPARATUS

Howard M. Threlkeld, Chicago, Ill., assignor, by
mesne assignments, to Reconstruction Finance
Corporation, Chicago, Ill., a corporation

Application January 15, 1935, Serial No. 1,807

9 Claims. (Cl. 62—126)

My invention relates in general to the separation of material from fluids carrying the same and has more particular reference to the separation of a lubricant from a refrigerant in a refrigerating system.

The process and apparatus of my present invention are particularly adapted for application in refrigerating systems wherein a fluid-refrigerating medium is circulated progressively to various parts of the system in performing its heat-exchanging function and wherein the refrigerating medium, in circulating in the system, may absorb or become mixed with a lubricating medium, employed in the system, to such a degree as to impair the heat-exchanging efficiency of the refrigerating medium and an important object of the invention resides in providing a simple, yet thoroughly effective means for and method of continuously separating and removing, from a refrigerating medium, lubricant which may have become entrained or dissolved therein during the circulation of the medium in the refrigerating system.

Another important object is to provide a method of abstracting quantities of an evaporable liquid, such as a refrigerating medium, from a body of the same, such as may be contained in the evaporator of a refrigerating system, which consists in utilizing gaseous pressure developed by the evaporation of the liquid in order to fluctuate the liquid level, in at least a portion of the liquid body, above and below a point at which the liquid may be drawn off, so that the removal of liquid may be accomplished only when the level rises above the removal point and hence is accomplished at a restricted rate controlled by the evaporation of the liquid.

Another important object is to provide for fluctuating the liquid level of the body, at the point of liquid removal, by utilizing the differential action of the pressure of the gases evolved in the vicinity of the removal point and the hydraulic pressure of the liquid head in remote portions of said body.

Another important object is to apply the method in the extraction from the liquid body of liquid containing a non-evaporable constituent whereby the evaporable constituent, which otherwise will remain entrapped in said body, may be removed; a further object being to separate and reclaim the non-evaporable constituent from the liquid removed from the body, preferably by evaporating the evaporable constituent from the removed liquid in order to obtain a non-evaporable constituent as a residue.

Another important object is to provide a refrigerating system containing a refrigerating medium adapted to change cyclically from liquid to gaseous form as it circulates in the system, the system containing fluid-forcing means for

circulating the refrigerating medium, and a lubricating medium for the fluid-forcing means which dissolves in the refrigerating medium when the same is in liquid condition, the invention including the provision of means, located in the system at the places where the refrigerating medium changes its condition from liquid to gas and adapted to extract the lubricant from the liquid refrigerant and return the same to the fluid-forcing means.

Another important object is to provide, in a refrigerating system including an evaporator and lubricated fluid-forcing means for circulating a fluid refrigerant to and from the evaporator, wherein the refrigerant is delivered to the evaporator as a liquid and discharged thence in gaseous form and wherein the lubricant, used to lubricate the fluid-forcing means, is soluble or miscible with or is of substantially the same specific gravity as the refrigerant so that the refrigerant and lubricant may not separate appreciably by stratification in the evaporator, and means for extracting the lubricant from the refrigerant in the evaporator and returning the same to the fluid-forcing means.

Another object is to provide an evaporator, having an exhaust outlet for removing gaseous products of evaporation, with a liquid outlet located in position to withdraw an evaporable liquid, containing a non-evaporable medium, from a body of the same contained in the evaporator, and a conduit associated with said outlet and through which the withdrawn liquid is caused to flow, said conduit extending in heat-exchange relationship with respect to the exhaust outlet so that the evaporable constituent of the withdrawn liquid, traveling said conduit, may be evaporated by absorbing heat from the gaseous products of evaporation traveling said exhaust outlet as well as from the surrounding atmosphere in order thus to separate the evaporable and non-evaporable constituents of the liquid flowing through said conduit.

Another object is to coil the conduit about the exhaust outlet in order to effect heat-exchange relationship therebetween.

A further object is to provide for continuously removing from the evaporator, at a restricted rate, liquid refrigerant containing lubricant, evaporating the refrigerant constituent of the removed liquid by exposing it to the action of heat contained in gas previously evaporated in the evaporator and returning the residual liquid lubricant to the fluid-forcing means in condition to perform its lubricating function.

A further important object is to accomplish the return of the lubricating medium to the fluid-forcing means by utilizing the pressure of the refrigerating medium in gasified condition to enable the lubricant to be withdrawn at a restricted

rate from its entrapped position in the system and return the same to the fluid-forcing means.

A further object is to continuously remove, from the evaporator, liquid refrigerant containing dissolved lubricant, evaporate the refrigerant constituent of the removed liquid in the vicinity of the evaporator in order to separate the constituents of the removed liquid without sacrificing the refrigerating ability of the refrigerant constituent and then return the separated constituents to the fluid-forcing means.

A further object is to return the liquid lubricant, the evaporated constituent of the removed liquid, as well as the gases evolved by evaporation of the refrigerant in the evaporator, to the fluid-forcing means through a common conduit.

Yet another object is to cause the refrigerant constituent of the liquid removed from the evaporator to evaporate as the same is returned to the fluid-forcing means in order to separate the lubricant by distillation of the refrigerant so that the separated lubricant may be delivered to the fluid-forcing means.

Still another object is to utilize the expansive effect of evaporation of the refrigerant constituent of the liquid removed from the evaporator to force the separated lubricant constituent on its way back to the fluid-forcing means.

A still further object is to form the evaporator with an evaporator space including an upwardly extending arm connected with the remaining portions of the evaporator space below the upper end of the arm so that the arm is or may be supplied with a column of liquid under pressure of the liquid head in the other portions of the evaporator space, an extractor conduit being connected in the arm at a point below the level of the liquid head in the remaining portions of the evaporator space so that, as a result of the differential between the substantially constant pressure, applied on the column of liquid in the arm, by the head pressure of liquid in the remaining evaporator space, and the variable pressure applied on said column by gases evolved in the upper end of said arm by refrigerant evaporation therein, the liquid level in said arm may be caused to fall and uncover the end of the extractor tube and permit the evolved gases to be drawn out of said arm, thus permitting the liquid level in the arm to rise and cover the extractor conduit, so that said extractor conduit may alternately and successively receive liquid from said arm and gases evolved in said arm as a result of evaporation of refrigerant therein and thus permit the liquid to be withdrawn from the evaporator at a restricted or controlled rate.

Numerous other objects and advantages and inherent functions of the invention will be apparent as the same is more fully understood from the following description, which, taken in connection with the accompanying drawing, discloses preferred embodiments of the invention.

Referring to the drawing:

Figure 1 is a diagrammatic view of a refrigerating apparatus containing lubricant separating means embodying my present invention;

Figure 2 is a plan view of a part of the refrigerating system shown in Figure 1 and containing the lubricant separator;

Figure 3 is a sectional view taken substantially along the line 3-3 in Figure 2;

Figure 4 is a diagrammatic view showing the elements of an evaporator having a lubricant extractor in accordance with my present invention;

75 and

Figure 5 illustrates a modified arrangement of the separator shown in Figure 3.

To illustrate my invention, I have shown on the drawing, refrigerating mechanism comprising a circulating system, including an evaporator 11, a fluid-forcing device 13 connected with the evaporator and adapted to draw the refrigerating medium in gaseous condition from the evaporator, compress and deliver the same thence through a condenser 15, in which the compressed refrigerant is liquefied, a dehydrator 17, and a flow control 19, back to the evaporator. The refrigerating medium is thus delivered in the evaporator in liquid condition, boils or evaporates therein and absorbs heat from the walls of and atmosphere surrounding the evaporator. The gases, evolved in the evaporator as a result of refrigerant evaporation therein, are drawn off by and returned to the fluid-forcing device 13 for a repetition of the refrigerating cycle.

The dehydrator is not an essential part of the system but may be used in order to ensure removal of any moisture which may be present in the refrigerating medium when initially loaded in the system. The dehydrator, if used in the system, and the flow control may have any suitable or convenient form, although I prefer to utilize a float controlled valve of the character illustrated.

The fluid-forcing device 13, also, may be of any suitable or convenient form and construction, although I prefer to utilize a compressor of the character shown in the application of Mahlon W. Kenney and Arthur R. Constantine for United States Letters Patent, Serial Number 724,894, filed 35 the 10th day of May, 1934.

It is ordinarily desirable to lubricate the fluid-forcing means and for this purpose a suitable lubricating medium, preferably a mineral oil, may be employed. The refrigerating medium, in traveling through the compressor, may dissolve, entrain, or otherwise pick up a part of the lubricant and carry the same from the compressor into the condenser where the lubricant mixes intimately or dissolves with the refrigerating medium as the same liquefies in the condensers. The lubricant, thus mixed or dissolved with the refrigerant, will be carried into the evaporator and since the return connection from the evaporator to the compressor must necessarily be made in the evaporator above the level of the liquid refrigerant head therein to prevent return of the refrigerant to the compressor in liquid condition with consequent loss of refrigerating efficiency, and further, since lubricants do not evaporate at the temperatures prevailing in the evaporator, the lubricant, carried into the evaporator with the liquid refrigerant, will accumulate therein and eventually choke the evaporator.

While I may use any suitable refrigerating medium, I prefer, for various practical considerations, to employ dichloromethane, which is substantially odorless, non-explosive, and non-poisonous.

Dichloromethane has a characteristic ability to dissolve ordinary lubricants and particularly mineral oils, such as I prefer to employ in lubricating the compressor. Consequently, the lubricant carried to the evaporator will not stratify therein by flotation. Other refrigerants, which make no solution with the lubricating medium may, however, form so intimate a mixture as to prevent separation of the components as to be substantially inseparable by flotation in 75

the evaporator. This is particularly true where the lubricant and refrigerant when liquid are of approximately the same specific gravity. The liquid in the evaporator consequently will be a homogeneous solution or mixture of the refrigerant and the lubricant and, if no provision is made for abstracting the lubricant constituent, the liquid will contain an ever increasing proportion of lubricant approaching a condition in which all of the lubricant, contained in the system for the purpose of lubricating the compressor, will become entrapped in the evaporator so that its efficiency is seriously impaired, if not entirely destroyed, while the compressor, at the same time, will be deprived of needed lubrication.

In order to prevent such a condition, I provide a simple inexpensive arrangement whereby lubricant is abstracted from the evaporator as rapidly as it accumulates therein and returned to the compressor. This I accomplish by providing a connection for continuously removing a small stream of liquid from the evaporator at a point below the normal liquid level therein, evaporating the refrigerant constituent of the abstracted liquid and returning the evaporated constituent together with the lubricant constituent of the abstracted liquid to the compressor.

In accomplishing the return of the lubricant in this fashion from the evaporator to the compressor, I utilize not only the pressure of the liquid head in the evaporator but also the pressure generated by the evaporation of the refrigerant constituent of the liquid abstracted from the evaporator as well as the suction produced by the compressor in drawing the evaporated gases from the evaporator, in order to cause the return of the lubricant.

The evaporator 11 may, of course, be of any suitable form or construction and, as shown in the drawings, may comprise a hollow shell-like vessel, preferably comprising sheets 21 and 23 of heat-conducting material formed so that, when fitted and secured together, a refrigerant evaporating chamber is formed between the sheets. To this end, the sheet 21 is preferably embossed with spaced header forming depressions 25 near its opposite ends, and, at least, one of the sheets, preferably the sheet 21, is embossed to provide a series of preferably parallel grooves 27, so that, when the sheets are fastened together in facing relationship, the depressions 25 and the grooves 27 form a chamber comprising spaced header portions 29 and ducts 31 interconnecting the header portions. The depressions 25 and the grooves 27 are preferably both formed in the sheet 21 and the other sheet is assembled in position to overlie the depressions and grooves, the sheets being secured together as by curling the edges of one sheet about the edges of the other as shown at 33 and sealing the curled edges in any suitable fashion, as, for instance, by welding or brazing.

The sheets may also be sealingly secured together around their peripheral edges and between the grooves 27 by welding, brazing, or by other suitable sealing means. The sheet 23 may also be formed with depressions 35 in position to register with the depressions 25 of the co-operating sheet in order to form elongated substantially cylindrical header chambers as shown in the drawing. One of the sheets, preferably the sheet 23, is also formed at intervals with depressions or grooves 37 forming ducts intersecting and communicating with the ducts 31. The formed sheets 21 and 23, after having been se-

cured together, may be bent to provide an evaporator having substantially U or channel shaped cross-sectional configuration substantially as shown in Figure 1 and having spaced apart side walls 39 and an interconnecting bottom wall 41, the side walls containing the header chambers 29 near their upper edges and the refrigerant ducts 31 extending beneath the header spaces in the side walls 39 and in the bottom wall 41. The embossed portions 27 project outwardly of the side and bottom walls and the ridges 37 project inwardly on the facing surfaces of the side walls and preferably form pairs of registering ridges upon and between which objects to be cooled may be supported. The opposite ends of the sheets 21 and 23 form the upper edges of the spaced walls of the evaporator and may be flanged as at 43 to provide means for hanging or otherwise mounting the evaporator in operative position as in the cooling chamber of a refrigerator.

The evaporator is provided with an inlet connection, which is preferably at or near the bottom wall 41, and through which liquid refrigerant may be delivered into the evaporator space at a point below the header chamber. To this end, I prefer to utilize one of the ridges 37 in order to form an inlet header. The ridge so employed is provided with an opening at one end, in which is mounted an inlet fitting 45 adapted for connection with a suitable pipe or conduit 46, through which the liquid refrigerant is delivered to the evaporator. The evaporator is also provided with an outlet for the vaporized refrigerating medium, which outlet preferably comprises a fitting 47 secured in an opening preferably formed in the sheet 23 opposite one of the header spaces 29. The fitting may have an extension comprising a pipe or conduit 49 extending within the header space and having an end opening above the normal liquid level in the evaporator. The fitting 47 is also provided for connection with the suction side of the compressor 13 as by means of a suitable pipe or conduit 48. The outlet fitting 47 may, of course, be connected in either or both of the headers but I prefer to connect the fitting 47 in one header only and to interconnect the header chambers by means of a conduit 51 fastened between the header forming portions 35 so that gaseous refrigerant evolved in one header chamber may escape through the conduit 51 into the other and then be withdrawn together with the gasified refrigerant evolved in said other chamber through the fitting 47 to the suction side of the compressor.

When the evaporator is in operation, the liquid level therein is normally maintained at an elevation substantially indicated by the dotted line 53 in Figures 4 and 5 of the drawing. The outlet pipe 49 opens substantially above said level. The refrigerating medium, which I prefer to use in the system, comprises dichloromethane and the system is preferably operated under conditions such that the liquid refrigerant will boil at the temperature prevailing in the vicinity of the evaporator.

In order to separate and extract the lubricant entrapped in the evaporator and return the same to the compressor, I provide the evaporating space in the evaporator 11 with an upwardly extending duct or riser 57 connected with the remaining portions of the evaporator space at a point below the upper end of the duct. This may be accomplished by blocking communication of an end of one of the ducts 31 with the header space to which the corresponding ends of the other ducts are con-

nected. This blocked duct, forming the riser 57, is connected with the remaining portions of the evaporating space at a point substantially below its blocked upper end by means of the lateral ducts formed by the grooves 37. The blocked duct in effect comprises one arm of a manometer, the other arm of which comprises the remaining portions of the evaporator space between the plates 21 and 23. The riser 57 will consequently become 10 filled with liquid refrigerant under the pressure of the liquid head maintained in the other portions of the evaporator, the refrigerant entering the riser 57 through the cross ducts 37. The refrigerant will evaporate in the riser 57 so that a 15 certain amount of gas will accumulate in the upper end of the closed riser 57.

A conduit 59, comprising a tube of relatively small internal size is connected with the riser 57 at a point below the level of the liquid head in 20 the main portion of the evaporator, the conduit 59 being preferably sealed in an opening in one of the plates 21 or 23, preferably the latter, in position to communicate with the riser 57. This conduit is connected with the suction side of the 25 compressor 18, preferably by connecting the same in a lateral opening formed preferably in the upper side of the fitting 47.

As shown in Figures 1, 2, 3, and 4, the conduit 59 may comprise a continuous piece of tubing connected at one end with the riser 57 and at the other end with the fitting 47, the tubing is also 30 preferably coiled in order to increase the length of the same between the riser 57 and the fitting 49 and, in order to conserve space, the tube 59 35 may be coiled about the fitting 47 as shown. Since the conduit 59 is connected with the suction side of the compressor, the gases, collecting in the upper end of the riser 57, will be drawn into the outlet fitting through the tube 59, which, although of restricted bore, will offer substantially 40 no resistance to the passage of the gaseous refrigerant which collects in the upper end of the riser 57. As the gaseous refrigerant is exhausted from the upper end of the riser 57, the liquid level 45 will rise therein under the pressure exerted by the liquid head in the main part of the evaporator until the liquid covers the end of the tube 59, at which instant a slug of liquid, comprising refrigerant and lubricant will be drawn into the tube 59. The surface tension of the liquid in the tube 59 50 will retard the passage of the liquid through the restricted bore of the same. In the meantime, the liquid refrigerant in the riser 57 continues to evaporate so that gases, accumulating in the 55 upper end of said duct, will gradually force the liquid level in the duct below the opening of the conduit 59 therein so that the gasified refrigerant may be drawn into the conduit 59 behind the slug of liquid. This cycle is repeated continuously as the evolved gases in the upper end of the 60 riser 57 are alternately withdrawn and permitted to accumulate. A succession of liquid slugs, separated by gasified refrigerant are thus caused to travel through the conduit 59, the slugs being 65 drawn partly by the suction exerted in the line 48 and the fitting 47 by the compressor and partly being forced by the propulsion developed behind each slug by the evaporation of the refrigerant. As the slugs of liquid travel the conduit 59, the 70 evaporable constituent thereof will be vaporized by absorbing heat through the conduit 59 from the surrounding atmosphere. The length of the conduit 59 and its internal size may be selected to ensure that all of the evaporable constituent 75 of each slug drawn successively into the conduit

will have been evaporated by the time said slug reaches and enters the fitting 47. Consequently, the components of the liquid, forming the slugs, will have been separated entirely into the gaseous refrigerant and the liquid lubricant by the time 5 said materials enter the suction line to the compressor. The lubricant, therefore, enters the fitting 47 in substantially separated condition and is drawn through the suction line together with the gasified refrigerating medium, with which the 10 lubricant will not mix or form a solution, and enters the compressor in condition to perform its lubricating function.

The evaporator, including the riser 57, and the lubricant extracting conduit 59 may be 15 formed to provide a regulating effect whereby to prevent the travel of liquid through the conduit 59 in a continuous stream and to ensure that liquid escapes from the evaporator only at a restricted rate. The length of the riser 57 from its 20 upper end to its point of connection with the main portions of the evaporator space and the internal diameter or bore of the conduit 59 may be so selected that the resistance of the conduit to the flow of liquid therethrough will be such 25 that if the conduit becomes choked with liquid, the pressure of the gases entrapped in the upper end of the riser 57, which pressure is determined by the head of liquid in the main evaporator space above the level of liquid in the riser, will be 30 insufficient to force the liquid through the conduit until the evaporable constituent of the same shall have become evaporated and the stream, flowing in the conduit, broken up into a succession of 35 slugs.

When the evaporator is initially placed in operation, or whenever the accumulation of gas in the upper end of the riser 57 takes place too slowly, the liquid level in the riser may cover the attached end of the conduit 59 for a period sufficient to permit the conduit to become entirely 40 or at least substantially full of liquid. It is desirable in such cases to provide means for preventing the liquid from continuing through the conduit 59 until such time as its evaporable constituent has at least become partially evaporated. This may be accomplished by properly selecting 45 the conduit with respect to the size of its internal bore and by arranging the length of the riser 57, between its upper end and its point of connection 50 with the main evaporator space, so that the maximum gas pressure in the riser, even when the same is entirely filled with gas, is insufficient to force the liquid column through the conduit against the resistance to liquid flow provided by 55 the restricted nature of the conduit channel. By properly choosing the internal diameter of the conduit 59 and the length of the riser, it is thus possible to prevent liquid from entering the conduit as a continuous stream beyond a predetermined distance even when the end of the conduit, which is connected in the riser, remains covered by the liquid level in the riser.

I have discovered that the boiling point of a 65 solution of oil in dichloromethane varies with the proportions of the media forming the solution. The boiling point of oil-free dichloromethane is slightly above one hundred degrees Fahrenheit. As oil is added in solution, the boiling point of 70 the solution increases slowly and substantially as a straight line function until the solution comprises approximately sixty percent oil. As the solution increases in oil content from sixty percent to eighty-five percent, its boiling point increases at a variable though increasingly rapid 75

rate. The boiling point of the solution, containing above eighty-five percent oil, increases at a substantially uniform, though rapid rate, with increase in oil content, the boiling point of refrigerant free oil being approximately three hundred and fifty degrees Fahrenheit, although this figure varies considerably for the different oils that may be employed as a lubricating medium in refrigerating systems employing dichloro-
10 methane as a refrigerant.

It will be seen from the foregoing that greatest efficiency will be had by exposing the liquid, traveling the conduit 59, to the boiling temperature of a solution containing from sixty to eighty-five percent oil, since such a temperature will ensure the evaporation of the refrigerant substantially entirely from any solution containing less than sixty to eighty-five percent oil to the end that the liquid, discharged from the conduit 59, will comprise between sixty and eighty-five percent oil which is entirely satisfactory for lubricating purposes in the fluid-forcing device. The additional refrigerant extractable from the solution traveling the conduit 59 by heating the same above the boiling point of an eighty-five percent oil solution is not of sufficient importance to warrant the provision of means to apply the additional heat particularly in view of the relatively rapid increase in boiling temperature with 30 increase in oil content above eighty-five percent. Of course, it is ordinarily not expected that the evaporator itself will ever contain refrigerant having as much as seventy percent oil in solution therewith. In fact, the system when properly operating, will rarely if ever permit as much as one percent of oil to remain entrapped in solution in the refrigerant in the evaporator.

It will be seen from the foregoing that substantially all of the refrigerant, which enters the fitting 41 and including that entering said fitting through the conduit 59, is in gasified condition so that no loss in refrigerating efficiency is entailed by withdrawing the refrigerant from the evaporator in liquid condition into the conduit 59. The arrangement, however, provides for the positive and continuous removal of the lubricant from the evaporator as rapidly as the same is drawn into the evaporator with the liquid refrigerant delivered thereto so that the evaporator at no time contains enough lubricant to impair its efficiency.

In Figure 5, I have shown an arrangement wherein the conduit 59 empties into a small receptacle 61, which may be mounted on the evaporator. An ejector conduit 63 extends from the receptacle 61 and enters the suction line. In this embodiment, it is unnecessary to extend the conduit 59 and coil the same in order to ensure the entire evaporation of the refrigerant constituent of the liquid withdrawn from the duct 57, since the receptacle 61, into which the liquid is delivered, is of a size to permit heat transfer, to the liquid therein, with sufficient rapidity to ensure the entire evaporation of the refrigerant constituent thereof while the same is in the receptacle. Consequently, the receptacle will be filled primarily with evaporated refrigerant with a film of liquid in the lower portions of the receptacle. The end of the ejector pipe 63 is disposed in the receptacle slightly above the bottom thereof so that it will normally permit the evolved refrigerant to be drawn out through the ejector pipe but will draw the lubricating medium 70 through the pipe 63 as rapidly as the same ac-

cumulates in the receptacle to a depth sufficient to cover the end of the pipe 63.

The arrangement shown in Figure 5 thus permits the lubricant to be delivered into the suction line in relatively larger quantities than is the case with the arrangements shown in the other figures of the drawing, in which the lubricant enters the suction line as a succession of relatively small drops.

I prefer, however, to employ the coiled pipe 10 arrangement shown in Figures 1, 2, 3, and 4, since the same is of simple construction and inexpensive, and will remove as much lubricant from the evaporator during an equivalent time interval as will the arrangement shown in Figure 5. 15

It is thought that the invention and numerous of its attendant advantages will be understood from the foregoing description and it is obvious that numerous changes may be made in the form, construction, and arrangement of the several 20 parts of the illustrated apparatus without departing from the spirit or scope of my invention or sacrificing any of its attendant advantages, the preferred modes and forms herein described being merely for the purpose of illustrating the 25 invention.

Having thus described my invention, what I claim as new and desire to secure by Letters Patent is as follows:

1. The process of abstracting a relatively non- 30 evaporable medium from a body of an evaporable liquid containing the same, which comprises maintaining the liquid level in remote portions of said body at different altitudes, confining and utilizing the pressure of gases evolved by the 35 evaporation of the evaporable liquid in the portion of lesser altitude differentially against the hydraulic pressure exerted by the liquid head in the other portion of said body in order to depress the altitude of the liquid level in the portion of 40 lesser altitude to permit removal of the evolved gases and liquid containing the non-evaporable medium alternately at a point intermediate the upper and lower altitude limits of the liquid level in said portion of lesser altitude. 45

2. A refrigerating apparatus comprising an evaporator and associated fluid-forcing means adapted to deliver an evaporable liquid, containing a relatively non-evaporable lubricant, to said evaporator, said evaporator being formed to provide a main evaporating chamber and a riser, connected below its upper end with the main evaporating chamber, whereby the presence of liquid in the main chamber will normally maintain liquid at a predetermined level in said riser, 55 an exhaust connection on the main evaporating space of the evaporator, at a point above the normal liquid level therein, said connection leading to said fluid-forcing means whereby gases, evolved by the evaporation of liquid in the main 60 evaporator space, may be drawn to the fluid-forcing means, an outlet in said riser substantially at the liquid level normally maintained therein whereby to permit liquid, containing lubricant, to enter said outlet and whereby the evolution 65 of gases in said riser by the evaporation of the liquid therein will cause the liquid level in the riser to drop below said outlet at intervals whereby to prevent escape of liquid continuously 70 through said outlet and to permit the evolved gases in said riser to escape through the outlet and thus permit the liquid to again rise above the same, and means connecting said outlet with the exhaust connection whereby the liquid and 75

gases, escaping through said outlet, may be returned to said fluid-forcing means.

3. A refrigerating apparatus comprising an evaporator and associated fluid-forcing means adapted to deliver an evaporable liquid, containing a relatively non-evaporable lubricant, to said evaporator and to withdraw from the evaporator gases evolved by the evaporation of the liquid therein, said evaporator being formed to provide a main evaporating chamber connected with the fluid-forcing means above the liquid level therein, and a riser connected below its upper end with the main evaporating chamber and adapted to receive liquid to a fluctuating level from the main evaporating chamber, an outlet in said riser substantially at the liquid level maintained in said riser, whereby said outlet may automatically be exposed above and submerged below said fluctuating liquid level and a conduit connecting said outlet with the fluid-forcing means whereby liquid, containing lubricant, may be withdrawn from said riser and delivered through the conduit to the fluid-forcing means whenever the outlet is submerged, said conduit extending in heat exchange relationship with a zone capable of supplying heat thereto to cause substantial evaporation of the evaporable constituent of the liquid passing therethrough before the same reaches the fluid-forcing means in order that the lubricant may be separated from the evaporable liquid and delivered in separated condition to the fluid-forcing means.

4. A refrigerating apparatus comprising an evaporator and associated fluid-forcing means adapted to deliver an evaporable liquid, containing a relatively non-evaporable lubricant, to said evaporator and to withdraw, from the evaporator, gases evolved by the evaporation of the liquid therein, said evaporator being formed to provide a main evaporating chamber connected with the fluid-forcing means above the liquid level therein, and a riser connected below its upper end with the main evaporating chamber and adapted to receive liquid from the main evaporating chamber to a fluctuating level in said riser, an outlet in said riser substantially at the liquid level maintained in said riser, and a conduit connected at one end with said outlet and having a remote end connected with the fluid-forcing means whereby liquid, containing lubricant, may be withdrawn from said riser and delivered through the conduit to the fluid-forcing means, said conduit being arranged in serpentine coils to increase its effective length, between said outlet and the remote end of said conduit, sufficiently to ensure the substantial evaporation of the evaporable constituent of the liquid traveling the conduit before the same reaches the remote end thereof.

5. A refrigerating apparatus comprising an evaporator and associated fluid-forcing means adapted to deliver an evaporable liquid, containing a relatively non-evaporable lubricant, to said evaporator and to withdraw, from the evaporator, gases evolved by the evaporation of the liquid therein, said evaporator being formed to provide a main evaporating chamber connected with the fluid-forcing means above the liquid level therein and a riser connected below its upper end with the main evaporating chamber and adapted to receive liquid from the main evaporating chamber to a fluctuating level in said riser, an outlet in said riser substantially at the liquid level maintained in said riser, whereby

said outlet may automatically be exposed above and submerged below said fluctuating liquid level, means forming a separator chamber, and means connecting said chamber with said outlet whereby liquid, containing lubricant, may be withdrawn from said riser, wherever the outlet is submerged, and delivered to the separator chamber, said chamber being arranged to permit evaporation of the evaporable constituent of the received liquid and the separation therefrom of the lubricant in said chamber, and means associated with said chamber for returning the separated lubricant and the evaporable constituent to the fluid-forcing means.

6. A refrigerating apparatus comprising an evaporator and associated fluid-forcing means adapted to deliver an evaporable liquid containing a relatively non-evaporable lubricant to said evaporator, said evaporator being formed to provide an evaporating space, an exhaust connection communicating the fluid-forcing means with said evaporating space above the liquid level therein whereby gases, evolved by the evaporation of liquid in said evaporating space, may be withdrawn therefrom and returned to the fluid-forcing means, a conduit connected with said evaporator in position to receive liquid, containing lubricant, and return the same to the fluid-forcing means, the intermediate portions of said conduit being disposed in heat-exchange relationship with said exhaust connection whereby to utilize the heat in the gases traveling therethrough to cause evaporation of the evaporable constituent of the liquid traveling the conduit so that the lubricant may be separated and returned to the fluid-forcing means in separated condition.

7. A refrigerating apparatus comprising an evaporator and associated fluid forcing means adapted to deliver an evaporable liquid containing a relatively non-evaporable lubricant to said evaporator, said evaporator being formed to provide spaced evaporating chambers and a plurality of interconnected ducts between said chambers, one of said ducts being closed at one end to communication with one of said chambers but in communication with the other of said chambers, whereby the fluid pressure of the liquid in the other ducts and in said other chamber will normally maintain the liquid at a predetermined level in said closed duct, an outlet in said duct below the liquid level normally maintained therein whereby to permit liquid containing a lubricant to enter said outlet, an exhaust connection between said fluid forcing means and the evaporating chambers at a point above the normal liquid level in the evaporator whereby gases evolved by the evaporation of the liquid in the evaporating chambers may be drawn to the fluid forcing means and means connecting said outlet with said exhaust connection.

8. In the combination of claim 7 wherein the means connecting the outlet with the exhaust connection comprises a coil of tubing encircling said exhaust connection.

9. In the combination of claim 7 wherein the means connecting the outlet with the exhaust connection comprises a receptacle mounted on the evaporator, a conduit connecting said receptacle to said outlet and a conduit connecting said receptacle to said exhaust connection.
